ARTIFICIAL LARYNX

Filed Oct. 8, 1931

UNITED STATES PATENT OFFICE

1,993,076

ARTIFICIAL LARYNX

Charles Sheard and Adrien N. Porter, Rochester, Minn., assignors to The Chemical Foundation Incorporated, New York, N. Y., a corporation of Delaware

Application October 8, 1931, Serial No. 567,570

1 Claim. (Cl. 3—1)

This invention relates to an artificial larynx or voice-box adapted to replace the human larynx in its cooperation with the other organs involved in phonation.

5 It has for its object the reproduction by artificial means of the functions of the larynx with relation to making and modulating vocal sounds, and more particularly to those sounds involved in and constituting speech, whose pitch ranges 10 between 90 and 300 cycles per second; and averages, for the female voice about 256 cycles, and for the male voice about 125 cycles, each second. In addition to its office as a vocal organ, our invention has for its further object to permit 15 inhalation and exhalation therethrough.

Further objects of our invention are herein-after more particularly pointed out.

In the accompanying drawing forming part of this specification, Figure 1 shows the voice-box 20 and connections assembled for use; Figure 2 is a view in vertical section of Figure 1, with the connecting elements indicated as broken away; Figure 3 is a like view on the line 3—3 in the direction of the arrows as shown on Figure 2, underlying parts being shown by broken lines; Figure 4 shows the reed-holder and reed; Figure 5 shows the reed-holder and groove therein; and Figure 6 is a view in horizontal section on the line 6—6 in the direction of the arrows as shown 30 on Figure 2.

Like numerals refer to like parts in the several figures, in which 1 is the voice-box proper, having the removable cap 2 thereon and the tubular extension 3 of this cap. 4 is the reed-holder and 35 5 is a groove therein terminating in an outlet 6 formed in the horizontal disk 7 constituting the top of the holder; 8 is the reed which is affixed to the holder by frictional engagement between it and a plate 9 held to the disk 7, as 40 by the screw 10, the plate 9 having a flange 11 between which flange and the face 12 of the reed-holder the reed is fitted and further held by the spring or set of the flange. 13 is a tubular extension of the box and 14 is an aperture in the 45 box. 15 is a flexible tube for insertion in the mouth. 16 is a flexible tube for connection to the tube 17 extending from the cupped plate 18, which is adapted to be applied to a tracheotomy opening in the neck. The neck-connection 50 shown is merely illustrative of an operative device, as the physical or anatomic characteristics of each individual, the shape and size of the tracheotomy opening, the presence or absence of a tracheotomy tube and other similar conditions 55 peculiar to the individual, necessarily mod-

ify the mode of attachment or placement of the voice-box to the neck.

Prior devices with which we are familiar differ fundamentally from our invention, as such instruments are of the fixed reed type. The disadvantages of that type, among others, are: the necessity for frequent adjustment of the reed; 5 breakage of reeds; inconstancy of pitch; the considerable pressure and volume of air required for operability; liability to jamming of the reed 10 when loud speaking is attempted; and inability of the user to lower the voice to a subdued tone in conversation. These physical handicaps are productive of uncertainty in the operation of such prior instruments, with resultant lack of 15 assurance on the part of the users.

Our invention avoids all these obstacles by the use of a beating-reed fixed at one end only, in conjunction with a holder therefor having a curved face, and a groove the depth of which is 20 graduated to decrease from the end at which the reed is fixed to the end over which the reed is freely suspended, as shown in Figure 2. The reed is broader than the groove, as shown in Figure 3, and constitutes what is termed a beating-reed. 25

By the curvature of the surface of the holder and the use of a reed broader than the groove therein, the reed bends with a rolling motion as it gradually covers the groove until it tends to 30 close it at each vibration, as hereinafter more fully described.

In the embodiment of our invention illustrated, the relative proportionality of the parts is that which has been proven by extended use to afford 35 the best results. The dimensions of these parts are substantially as follows:

The reed, which is preferably of hard-rubber, is between .015 and .016 inch in thickness, but such thickness may range between .012 and .018 40 without detriment to its desired mechanical and vibratory characteristics. The breadth of the reed at its fixed end is $\frac{1}{8}$ inch, and it tapers to a breadth of $\frac{1}{4}$ inch toward the rounded end which is elliptic, as shown, but these dimensions 45 and configuration are not essential, as the breadth is determined by the width of the groove which it must exceed in order to cover it and leave a margin of the reed overlying the curved face of the holder. While the length of the reed here shown approximates 1.5 inches, the length thereof free to vibrate is determined by the pitch 50 of the voice of the user. Thus shortening the reed, as by cutting off the upper end, increases the vibration frequency and raises the voice pitch. 55

The length of the reed must be proportioned in accordance with the requirement of each individual.

The groove in the holder is preferably $\frac{1}{8}$ inch wide, and its depth is graduated from $\frac{1}{8}$ at the bottom to $\frac{1}{4}$ at its top. The hole in the plate forming the top of the holder in communication with the groove tapers to a diameter of .205 inch. These determinations were found to permit the greatest velocity of air through the slit formed between the reed-tip and the planar face terminating the holder below the groove, while affording the maximum volume of air for a minimum pressure.

The reed-holder is positioned in the box by means of the disk forming its top, which is peripherally seated upon the upper edge of the tubular box and held thereto by an interior shoulder in the removable cap which is threaded to screw upon the box, but any suitable mechanical means may be used in mounting the reed-holder in the box without departure from the spirit of our invention.

The curvature of the face of the holder upon which the reed beats is not uniform. It is preferably flat at the point of insertion of the reed and substantially so for approximately quarter of an inch from that point. The curvature thereafter is slight for substantially half an inch, and then its degree increases for the next quarter inch, and then further increases to the extremity of the holder, which extends about a quarter inch beyond the end of the groove. With this contour, the flexible reed can bend so as to come down smoothly and flat, and thus progressively shut off the air passage from the base, or fixed end, to the tip, or free end; so that as the closure proceeds, it does so with certainty and uniformity, and the reed gradually covers the opening, with constant and even diminution of the air stream.

The vibratory action of the reed is to bend on the face of the holder like a covering flap until it has nearly closed it. The beating reed, when adjusted, or voiced, closes with a rolling motion and thus gradually covers the aperture of the groove, whereby the harshness of quality consequent upon a sudden discontinuity is obviated. (Glazebrook's Dictionary of Applied Physics.)

The diameter of the interior of the cylindrical portion of the box is one-half inch, and its length approximately two and a quarter inches. The upper tubular extension is $\frac{1}{8}$ inch, and the lower is $\frac{1}{4}$ inch. The opening in the side of the box is about $\frac{1}{8}$ inch.

The function of the aperture 14 is to permit passage of air through the box to the lungs of the user. It is normally closed by the thumb of the user, the thumb being removed when he needs to inhale or exhale.

In the form of neck-construction illustrated, the cupped-plate carries a valve, not shown, for purposes of breathing, should the user fail to remove his thumb. This neck-construction is

shown merely as a conventional accessory to our invention, which may be attached in any desired manner, either with the rubber-tubing connecting it to the neck-piece shown, or by a solid metal piece between the neck-plate and voice-box; or, when a tracheotomy cannula is worn, its tube may be bushed and connected by rubber tube to the voice-box.

With our invention, the following features of advantage are attained which have not heretofore been realized save in minor degree: the length of the reed may be initially adjusted to allow the person using the artificial larynx to have his natural tone of voice; the reed when initially adjusted requires no further adjustment to keep it in operative condition; the user may enjoy a normal tone range and speak in a low whisper or talk loudly without loss of volume in the low speech range or jamming of the reed by loud speech; the collection of moisture between the reed and the holder is prevented by the curvature of the contact face of the holder, whereby freezing of the reed to the holder is obviated together with the tendency of a moist reed to cling to the holder and stick in cold weather, conditions which made prior devices non-useable at low temperatures; no unusual effort is required on the part of the user to operate our device, due to the size of the groove in the reed-holder and the air-passages provided, whereby a very low pressure gives a maximum volume of air therethrough.

Our invention is susceptible of adaptation and application in variously modified forms, as will be apparent to those skilled in the art; and we do not intend to be understood as limiting it to the particular embodiment thereof herein shown and described, save as may be required by the scope of the appended claims, wherein the word "reed" is used to denote a vibratory element of the freely suspended type, namely, a flat beating-reed of thin hard rubber which is neither reinforced, stiffened or weighted, and which is adapted to seat directly upon its support without any intervening medium.

What we claim and desire to secure by Letters Patent is:

An artificial larynx comprising, a cylindrical air-chamber having a cap and a tubular extension from said cap; a reed-holder comprising a circular plate and a channelled member depending therefrom; the said plate being held peripherally against the upper edge of the air-chamber by said cap; an orifice in said plate communicating with said channel; a beating-reed fixed at its upper end to said reed-holder and covering the channelled front thereof; and a tubular extension from the bottom of said chamber, whereby an air passage is afforded extending from and through the bottom extension to and through the cap extension and including the reed-covered channel.
